UNITED STATES PATENT OFFICE

2,548,629

ELECTRICAL INDUCTION APPARATUS

Gareth G. Somerville, Pittsfield, Mass., assignor to General Electric Company, a corporation of New York

Application June 5, 1947, Serial No. 752,620, which is a division of application Serial No. 655,961, March 21, 1946. Divided and this application November 4, 1949, Serial No. 125,564

1 Claim. (Cl. 175—356)

1

This invention relates to electric induction apparatus and more particularly to improvements in such apparatus comprising a curved core.

This is a division of my application, Serial Number 752,620 filed June 5, 1947, now Patent No. 2,534,312, which in turn is a division of my application, Serial Number 655,961 filed March 21, 1946, and assigned to the same assignee.

As here used the term "curved core" means a core having a plurality of radially nested flatwise curved lamination layers. Any desired number of such cores may be linked with the same winding so as to constitute a multiple part core. This is usually done to improve the space factor of the window of the winding.

This invention is characterized by a novel frame for cradling such a core and also clamping it properly as to support it and the winding or windings linking it.

An object of the invention is to provide a new and improved electric induction apparatus.

Another object of the invention is to provide a new and improved method of assembling an electric induction apparatus.

A further object of the invention is to provide a new and improved frame assembly for a curved magnetic core.

The invention will be better understood from the following description taken in connection with the accompanying drawing and its scope will be pointed out in the appended claim.

In the drawing, Fig. 1 is a front elevation view, partly broken away, of an induction apparatus embodying my invention, Fig. 2 is a front elevation view of a multi-part curved core suitable for use in my invention, and Fig. 3 is a side view of the lower part of the apparatus shown in Fig. 1.

Referring now to the drawing and more particularly to Fig. 2, the illustrated core is a single-phase distributed type core having a central winding leg 1 and a divided yoke 2. As seen in this figure, it is symmetrical about a vertical center plane which is perpendicular to the paper and the duplicate right- and left-hand halves comprise three nested core members 3, 4, 5 and 6, 7, 8, respectively. Actually the core is also symmetrical about a second plane at right angles to the dividing plane referred to above and which is parallel to the paper in Fig. 1 so that the right- and left-hand halves of the core actually each consist of six core elements, the ones directly in front and in back of the last-mentioned plane being duplicates. As seen in Fig. 1, the core elements each have a single joint 9 which is at the upper end of the straight winding leg in each

2

case. As shown in this figure, these joints appear successively to be staggered instead of being in vertical alignment and this is necessary so that when the core elements are opened up for receiving a conductive winding they will not extend over beyond the dimensions of the coil window.

The six core parts are held firmly together by tie straps 10 which are relatively wide so as to have the necessary area to provide adequate strength and at the same time are relatively thin so that there is comparatively little separation between the front and back core parts. Preferably they have shoulders 11. These straps extend slightly beyond the right and left edges of the winding leg 1 and the ends of the straps pass through openings in washer plates 12, which may be made of any suitable material such as press-board, and outer steel plates 13 to which the ends of the straps are welded.

20 A view of an assembled electric induction apparatus embodying the invention is shown in Fig. 1. In this figure the core is cradled in a frame comprising angle iron members 14 which are held together by cross members 15 which are bolted thereto. Upright angle iron members 16 serve to clamp the yoke portions 2 of the core and flexible metal strap members 17, as shown more clearly in Fig. 3, which are fastened to cross pieces 18 attached to the members 16 serve to support the weight of the core. These strap members 17 extend around underneath the core and are in tension and conform to the rounded shape of the bottom of the core. Additional cross members 19 on both the inside and outside of the upright members 16 serve to support the yoke members 2 of the core at both its inside and outside portions.

25 A coil 20 is supported by members 21 which are fastened to the bottom members 14 and which may be adjusted in any suitable manner so as to position the coil 20 properly. The top part of the core is clamped between members 22 which are bolted as at 23 to the upright members 16.

30 While there has been shown and described a particular embodiment of this invention, it will be obvious to those skilled in the art that various changes and modifications can be made therein without departing from the invention and, therefore, it is aimed in the appended claim to cover all such changes and modifications as fall within the true spirit and scope of the invention.

35 What I claim as new and desire to secure by Letters Patent of the United States is:

40 A stationary electric induction apparatus comprising, in combination, a curved core having a central winding leg and oppositely extending yoke

55

portions, said core having a generally rectangular outer configuration with rounded corners, a winding on said winding leg, a frame having two generally rectangular fabricated structural members of substantially the same configuration as the outer configuration of said core mounted respectively against the front and back of said core, cross pieces extending between said rectangular frame members for fastening them together, a plurality of flexible metal straps attached to two of said cross members on opposite sides of said core for cradling the bottom of said core and supporting its entire weight while at the same time conforming to the curvature of its bottom

corners, and coil supports mounted on said frame for engaging the bottom of said winding and maintaining it in proper position on said winding leg.

GARETH G. SOMERVILLE.
